UNITED STATES PATENT OFFICE

2,472,350

HOSIERY SUPPORTER

Roswell M. Taylor, Noank, Conn.

Application January 3, 1946, Serial No. 638,815

3 Claims. (Cl. 2-300)

1

This invention relates generally to hosiery supporters, and more particularly to a supporter for hosiery combined with the leg of an undergarment.

Usually men's socks are supported by leg encircling garters, which of necessity must be tight enough around the legs to keep them from falling down over the calf of the leg. Such garters are, in many cases, tight enough to obstruct the flow of the venous blood up the legs to the heart, which of course is an undesirable condition. Also, garters are a separate accessory which is often regarded as a nuisance. While it has been heretofore proposed to overcome the undesirable features of the leg encircling garter, by providing various kinds of supporters, which attach to the undergarment by pins or the like, nevertheless, these have been generally found unsatisfactory because they not only tend to tear both the underwear and the hosiery, and at the same time present difficulty in laundering.

Accordingly, the present invention provides a novel hosiery supporter, whereby the foregoing disadvantages are eliminated without sacrificing any of the efficiency of the supporter, by combining with another garment a novel supporter having a portion thereof incorporated as a permanent part of the leg of the garment, and a detachable hosiery supporting strap and fastener for use with other garments having a like portion of the supporter permanently incorporated therewith. In that connection a distinctive feature resides in providing the supporting strap with a button which serves the dual purpose of forming an anchor to connect the strap to the garment and also to receive the clasp for gripping the top of the hose.

With the foregoing and other objects in view, the invention will be more fully described herein-after as to several embodiments thereof, and will be more particularly pointed out in the appended claims.

In the drawings:

Figure 1 is a front elevation of the invention applied to a garment leg in assembled position.

Figure 2 is also a front view showing the permanently affixed guide and attaching strip or base for the garter strap.

Figure 3 is a perspective view of the garter strap as it appears when separated from the guide and attaching strip.

Figure 4 is a cross-section view taken along line 4-4 of Fig. 1.

Figure 5 is a front elevation of another form of the guide and attaching strip, and

2

Figure 6 is a cross-section view taken along line 6-6 of Fig. 5.

In its general aspect, the invention includes as a unit a garter strap supporting base or attaching strip of fabric which is woven, knitted, sewed or otherwise fastened to the leg of a nether garment to serve as a guide for receiving and mounting a sock supporting or garter strap having a key-hole type clasp or fastener secured to one end, and a button for interlocking a portion of the sock when it is stretched over the button head in the slot of the clasp.

Referring to the drawings, and first with particular reference to Fig. 2, the device comprises an elongated fabric attaching strip 10 secured longitudinally to the leg 11 of a nether garment, by any appropriate means as heretofore indicated. This strip 10 is provided with upper and lower transverse webs to provide an upper guide means, such as a top loop 12 and a lower loop 13, the latter having a button hole 14 therein for detachably anchoring the hosiery support or garter strap 15, such as shown in Fig. 3. This strap has one end thereof looped through the base portion of a key-hole clasp 17, and the other end looped through the base portion of a button 18. Said button 18 comprises a base 19, a shank 20, and a head 21 relatively larger than the shank.

As best shown in Figs. 1 and 4, the shank 20 of the button is projected through the button hole 14 from inside the lower loop 13, so that the button head 21 is exposed outside the loop. When this is accomplished, the strap 15 becomes anchored to the strip 10. The strap is then threaded upwardly under the guide loop 12 and dropped downwardly over the top edge of the loop, so that the key-hole clasp 17 dangles adjacent the head 21 of the button. With the two elements of the fastener in this position, the top portion 22 of a sock or the like may be placed over the head 21, and locked thereon by the small part of the key-hole clasp 17, as shown in Fig. 4.

Thus, there is provided a novel supporter for hosiery requiring no pins or cloth penetrating teeth, and having no leg encircling straps to interfere with normal blood circulation from the legs to the heart.

In Figs. 5 and 6, I have shown a modification of my invention, by providing a single strip of fabric 10a having two pairs of transverse slots 23, 24 and 25, 26 to provide intermediate webs 27 and 28. The web 27 provides the guide loop 12, and the web 28 provides the anchor loop 13 for strap 15 with its button hole 14a.

The strap 15 is applied to the strip 10 of this

form in the same manner as previously explained in connection with the first form, but as the loops are an integral part of the strip, as shown in Figs. 5 and 6, there is less sewing and less cloth in the fabric strip according to this form of embodiment.

Further modifications will be apparent to those skilled in the art, and it is intended, therefore, that the invention be limited only by the prior art and the scope of the appended claims.

I claim:

1. In a hosiery supporter, a guide and anchor strip for a detachable hose supporting strap having button head and key-hole fastener elements on each end thereof, said strip being permanently affixed to the leg portion of a garment, upper and lower web portions for receiving portions of said supporting strap, said lower web having a button hole therein adapted to secure the button head portion of the fastener to the strip under the lower web, whereby the strap is held in position for manipulation to support hosiery from the leg portion of the garment.

2. In a hosiery supporter, a strip of fabric sewed to the leg of an undergarment, said strip having two pairs of transverse slots at each end, to thereby provide upper and lower web portions between each pair of slots, said lower web portion having a button-hole therein, each of said webs forming guide loops for a hosiery strap supporter of the button and key-hole clasp type, and said button-hole being adapted to secure the button

head of the hosiery strap in the lower web to hold it in position for cooperation with the hose and the keyhole clasp on the other end of the strap.

3. In a hosiery supporter, a combined guide and anchor strip for a detachable hose supporting strap, said strap having mounted on one end a button head and having mounted on the other end thereof a key-hole fastener, said anchor strip being permanently affixed to the leg portion of a garment, and said anchor strip having a button hole in the lower portion thereof adapted to anchor the button head fastener on the strap to the strip, whereby the button head on the said hose supporting strap is held in position in the button hole of said strip to cooperatively engage within the keyhole fastener, to thereby support hosiery from the leg portion of the garment.
